UNITED STATES PATENT OFFICE

153,073

DESIGN FOR A CLOCK

John H. O'Brien, Maywood, Calif.

Application October 6, 1948, Serial No. 148,983

Term of patent 14 years

(Cl. D42—7)

To all whom it may concern:

Be it known that I, John H. O'Brien, a citizen of the United States of America and a resident of Maywood, county of Los Angeles, State of California, have invented a new, original, and ornamental Design for Clocks, of which the following is a specification, reference being had to the accompanying drawing, forming a part thereof.

In the drawing:

Figure 1 is a front elevational view of a clock, showing my new design.

Figure 2 is a top-plan view of the disclosure in Figure 1, and

Figure 3 is a side-elevational view thereof.

I claim:

The ornamental design for a clock, substantially as shown and described.

JOHN H. O'BRIEN.
